CLAIM

The ornamental design for a storage box, as shown and described.

DESCRIPTION

FIG. 1 is a top perspective view of a storage box showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of encircled portion 9 in
FIG. 1;

FIG. 10 is a partial enlarged view of encircled portion 10 in
FIG. 2;

FIG. 11 is a partial enlarged view of encircled portion 11 in
FIG. 2; and,

FIG. 12 is a top perspective thereof, shown in an opened configuration.

The dot-dash broken lines in FIGS. 1, 2, and 9-11, which form no part of the claimed design, encircle portions of the storage box that are illustrated in enlargements.

The evenly-dashed broken lines shown in FIG. 2 depict portions of the storage box that form no part of the claimed design.
